CLAIM

The ornamental design for a cabin for a transport vehicle, as shown and described.

DESCRIPTION

FIG. 1 is a right front perspective view of our cabin for a transport vehicle;

FIG. 2 is an enlarged right side view thereof;

FIG. 3 is an enlarged left side view thereof;

FIG. 4 is an enlarged front view thereof;

FIG. 5 is an enlarged rear view thereof; and,

FIG. 6 is a top plan view thereof.

The portion of the photographs in FIGS. 1-6 shown in a coarse dot pattern and outlined in dashed lines is included for the purpose of illustrating portions of the cabin for a transport vehicle and forms no part of the claimed design.
